UNITED STATES PATENT OFFICE.

ROBERT W. STEWART, OF FINDLAY, OHIO.

KILN.

SPECIFICATION forming part of Letters Patent No. 746,757, dated December 15, 1903.

Application filed January 13, 1903. Serial No. 138,928. (No model.)

To all whom it may concern:

Be it known that I, ROBERT W. STEWART, a citizen of the United States, residing at Findlay, in the county of Hancock and State of Ohio, have invented certain new and useful improvements in Kilns; and I do hereby declare the following to be a full, clear, and exact description of the invention, such as will enable others skilled in the art to which it applies to make and use the same.

The invention relates more especially to continuous kilns for burning brick, tile, pottery, and other ceramic products.

The objects of the invention are to insure the production of evenly-burned ware and to make use of the heat from ware burned or being burned by passing it through ware partially or wholly unburned, thereby saving fuel and time.

The invention consists in the construction hereinafter described and claimed, the claims not being limited to the specific construction shown.

In the accompanying drawings, showing an embodiment of the improvements, Figure 1 is a perspective view, ten ware-chambers being shown arranged in two batteries of five each, the passages of the end chambers of each battery being connected or supplemented by tunnels. Fig. 2 is a longitudinal vertical sectional view on the line 2 2, Fig. 4, through the center of one of the batteries. Fig. 3 is a transverse vertical section on the line 1 1, Fig. 4, through one of the tunnels. Fig. 4 is a horizontal section on the line 4 4, Fig. 2, showing on the left the plan of the flues directly under the floor and on the right a section above the floor. Fig. 5 is a transverse vertical section on the line 3 3, Figs. 2 and 4, through the burning-chambers. Fig. 6 is a detailed oblique view of the passage from the chimneys to the adjoining ware-chambers. Fig. 7 is a detail view of the top of a kiln and passages from the chimneys to the adjoining ware-chamber when the improvement is used on temporary brick-kilns, otherwise termed "scoved kilns," "Dutch kilns," &c.

In the several views A designates the fire-boxes or furnaces.

B designates the under floor-flues arranged in pairs, each pair leading in the opposite direction to that of the pair next to it. Each

pair of flues B leads at one end from a fire-box, while the other end communicates with a bag-flue or pocket F.

C designates footing courses upon which the under-floor-flue walls D are erected.

E is a thin tight floor resting directly upon the under-floor-flue walls D. The pocket or bag-flues F lead from the floor-flues to near the top of the ware-chambers.

G¹ G² G³ G⁴ G⁵ are ware-chambers in which ware is placed to be burned.

I¹ I² I³ I⁴ I⁵, &c., are chimneys having entrances H at their lower ends, but near the floors of the ware-chambers. The upper ends of the chimneys connect both with the open air and with the adjoining ware-chamber through passages M from the chimney through the crown of the kiln. The chimneys are furnished with slab-dampers J, adapted to close the opening to the atmosphere, and also with dampers K, adapted to be inserted through the top of the chimney by means of a handle L to close the opening. When the heat of one chamber is to be directed into the adjoining chamber, the damper J is put on and the damper K taken out, and when the gases are to be let into the atmosphere the damper K is inserted and the damper J removed.

N designates spaces in the lower portions of the outer walls of each of the end chambers which communicate with the said end chambers and with tunnels O, connecting the opposite end chambers, so that the heat from one end chamber can be directed to the end chamber of the opposite battery of kilns.

h designates auxiliary entrances to the chimneys, which normally are left closed, but are adapted to be opened and used to supplement the entrances H when desired.

The operation of the kiln is as follows: Suppose the three chambers G², G³, and G⁴ to be filled with ware. The heat and products of combustion pass from the furnaces A of the chamber G² through the flues B under the floor E to the bags F, heating the floor on the way. The heat is conducted through the thin tight floor, thereby helping to burn the ware in the bottom of the ware-chamber G². The heat then passes up the bag-flues F to a point almost at the top of the chamber, where it turns and passes down through the ware and escapes through the chimney-entrances H to

the chimney I². The heat and products of combustion then pass into the top of the chamber G³ down through the ware and into the chimney I³ through its entrance H. In the 5 mean time the heat from the furnaces A under the chamber G³ passes into said chamber G³ through its bag-flues F, thus combining with and supplementing that from the chamber G². The gases and heat are confined and 10 made to pass through successive chambers until all the available heat is made use of or until they become loaded with moisture, at which point the dampers K are inserted, thereby allowing such gases to escape into the atmosphere, as indicated by the arrows, Fig. 2, 15 in the chimney I⁴. In this way a part of the ware-chambers can be in operation while the others are being emptied or refilled. In case the last chamber of a battery is in operation 20 the heat passes down through the openings H into the tunnel connection N through the tunnel O to the connection N at the other end of the tunnel and thence to the chimney in the other battery.

25 In the form of the invention illustrated in Fig. 7 I prefer to build all or a part of the structure of unburned brick at the same time the ware-chambers are filled, the brick of the structure to be burned and marketed along 30 with the brick or other articles burned in the ware-chambers. In such case the top of the kiln can be built flat and tight and can rest directly on the ware in the chamber below, the ware being set loosely to a depth of several 35 inches below the tight plating. In said Fig. 7, P designates the tight plating of the top, and Q the open setting just referred to.

What I claim, and desire to secure by Letters Patent, is—

40 1. In a kiln, a series of ware-chambers, each having the following parts, to wit: a fireplace, under floor-flues, bag-flues connected at their lower ends with said under floor-flues and opening at their upper ends near the top of 45 the kiln, combined with chimneys between said ware-chambers each communicating with one of the adjoining ware-chambers and having openings discharging both into the atmosphere and into the adjoining kiln.

50 2. In a kiln, two batteries of ware-chambers, each ware-chamber of each battery having the following parts, to wit: a fireplace,

under floor-flues, bag-flues connected at their lower ends with said under floor-flues and opening at their upper ends near the top of 55 the kiln, combined with chimneys intermediate all the ware-chambers each chimney communicating with one ware-chamber and having openings capable of discharging either into the next ware-chamber or into the atmosphere and a tunnel connecting the end chambers of the two batteries.

3. In a kiln, the combination of a series of ware-chambers each having a furnace at opposite sides and under floor-flues extending 65 from each of said furnaces to the opposite wall of the ware-chamber, bag-flues in said walls connected at their lower ends with the exit ends of said under floor-flues and opening at their upper ends near the top of the 70 kiln, and chimneys between said ware-chambers communicating with the lower portion of one of the adjoining ware-chambers and having openings discharging both into the atmosphere and into the adjoining ware-chamber. 75

4. In a kiln, the combination of a series of ware-chambers each having a fireplace or furnace, under floor-flues, bag-flues connected at their lower ends with the exit ends of said under floor-flues and opening at their upper 80 ends near the top of the kiln, and chimneys between said ware-chambers each communicating with one of the adjoining ware-chambers and having openings discharging both into the atmosphere and into the adjoining 85 kiln and movable dampers for controlling the discharging-openings of said chimneys.

5. In a kiln, a series of ware-chambers, each having the following parts, to wit: a fireplace, under floor-flues, bag-flues connected at their 90 ends with said under floor-flues and opening at their upper ends near the top of the kiln, combined with chimneys between said ware-chambers communicating with the lower portion of one of the adjoining ware-chambers 95 and having openings discharging into the atmosphere and into the upper portion of the adjoining ware-chamber.

In testimony whereof I affix my signature in presence of two witnesses.

ROBERT W. STEWART.
